UNITED STATES PATENT OFFICE.

CHARLES P. POTIER, OF DORCHESTER, MASSACHUSETTS.

DESIGN FOR AN ADVERTISING DISPLAY CARD.

Application filed November 9, 1925. Serial No. 15,383. Term of patent 7 years.

To all whom it may concern:

Be it known that I, CHARLES P. POTIER, a citizen of the United States, residing at Dorchester, in the city of Boston, in the county of Suffolk and State of Massachusetts, have invented a new, original, and ornamental Design for Advertising Display Card, of which the following is a specification, reference being had to the accompanying drawing, forming part thereof.

The figure is a front elevation of the article showing my new design.

I claim:

The ornamental design for an advertising display card, as shown.

CHARLES P. POTIER.
